UNITED STATES PATENT OFFICE.

BENEDICT T. GIBBS, JR., OF CHICAGO, ILLINOIS, ASSIGNOR TO MORDEN FROG & CROSSING WORKS, OF CHICAGO, ILLINOIS, A CORPORATION OF ILLINOIS.

RAIL-BRACE.

1,365,680.

Specification of Letters Patent. Patented Jan. 18, 1921.

Application filed April 18, 1920. Serial No. 373,524.

To all whom it may concern:

Be it known that I, BENEDICT T. GIBBS, Jr., a citizen of the United States, residing at Chicago, in the county of Cook and State 5 of Illinois, have invented a certain new and useful Improvement in Rail-Braces, of which the following is a specification.

This invention relates to rail braces. The object of the invention is to provide a device of this class for use against one side 10 of a rail for adjustably laterally positioning it, and for rigidly securing it in position after wear has taken place between the rail and brace itself, and parts against which the 15 brace bears, the device being especially applicable to rails at and adjacent to switch points whose lateral movement to and from the unsupported side of the rail render the use of spikes or other securing devices impractical, also on guard rails or on rails 20 on heavy curves.

The invention consists in a device of this class in which the rail block proper moves only longitudinally of the base plate on 25 which it is mounted, thus insuring effective action of the device in all positions of adjustment; in which all parts of the device are always sufficiently attached to the base 30 plate so that it can be shipped intact and installed in the track without danger of parts being lost. More particularly the invention consists in such a device which can be easily and cheaply made, which is satisfactory in operation, and is not readily liable 35 to get out of order. More particularly the invention consists in features and details of construction hereafter more fully set forth in the specification and claims.

Referring to the drawings in which similar numerals represent the same parts 40 throughout the several views,

Figure 1 is a plan, and

Fig. 2 is a sectional view on the line 2—2, Fig. 1, illustrating the device of this invention in its preferred form.

Figs. 3 and 4 are corresponding views of a modified form of device.

In the structure of Figs. 1 and 2 the usual base plate 10 is provided adapted to be placed on top of an ordinary railroad tie, the same being provided in the case here illustrated with a surface recess having a bottom surface 12 and end walls 14 and 16 against the latter of which is placed a bearing block 18 held in place by any suitable

means as rivets 20 having a bearing face 22 extending across the base plate, generally parallel to the central axis of the rail 24 whose flange 28 normally abuts the wall 14, heretofore referred to. On the opposite side 60 of the rail 24 and over the opposite flange 30 is placed the brace block proper 32 having on its side adjacent to the bearing block 18 a wedge surface 34 longitudinally angular to the rail and base plate and vertically 65 inclined inwardly. Filling the angular space between this surface 34 and the surface 22 is a triangular wedge member 36 supported upon a horizontal base flange 38 lying under the base of the brace block 32 70 and occupying substantially the entire space between rail flange 30 and bearing surface 22. The face of block 32 which engages face 34 of the wedge is vertically inclined outwardly of the block to fit said face 34 so 75 that the wedge presents upward spring of the block along the surface 34. This base flange 38 of the wedge is provided with slots 40 parallel to the axis of the rail 24 while the adjacent portion of the brace block 32 80 is provided with slots 42 elongated in a direction at right angles to the rail 24. Each one of the slots 42 crosses an adjacent one of the slots 40 and through their intersection there rises from the base plate 10 a bolt 85 or the like 44, mounted in the base plate in any suitable manner and provided with a suitable nut 46 adapted when screwed down to securely clamp the brace block 32, the wedge flange 38, and the plate 10 all together.

The narrower portion of wedge 36 is provided with a horizontally extending top flange 48 extending over the adjacent angular edge of the brace block 32. This flange 48 and the adjacent portion of base flange 38 are provided with registering holes 50 through selective pairs of which, the cotter pin 52 is inserted as near as possible to the edge 56 of plate 10 and edge of brace 100 block 32 after the wedge has been driven to place.

In the operation of this structure assume that some wear has taken place at the surface 14 or between the rail and brace block 105 or anywhere else in the structure, and that the rail is to be adjusted so that wear of any parts is taken up. The operator simply loosens nut 46 until the wedge 36 can be moved whereupon he strikes the lower end 110

of the wedge 36 and drives it upward as viewed in Fig. 1. This forces the brace block 32 and the rail 24 to the left to a new position. As soon as this is reached the operator retightens nut 46 and inserts cotter pin 52 in the next hole 50 if any beyond the edge 56 of plate 10 and brace block 32.

There is sufficient clear space 58 between the base flange 38 of the wedge and the base 10 plate 10 so that when the nut 46 is tightened there is a strong leverage at the brace block 32 upon the base flange 38 of the wedge and upon the flange 30 of the rail, whereupon both the wedge and the rail are securely held 15 in place upon the base 10. This is important when the structure is used in connection with a switch point, (not shown) which has to move so close to the left side of rail 24 that spikes or other ordinary securing devices 20 cannot be inserted adjacent to the rail.

In the modified structure of Figs. 3 and 4 the base plate, rail and bearing block are the same, except that the substituted bearing block 60 has its bearing face 62 corresponding to face 22 of Fig. 1 located at an angle to the rail instead of parallel to it. In this modified structure, as before, there is a brace block 64 having in its portion immediately adjacent to the base plate 10 slots 66 elongated at right angles to the rail, so that this brace block may be moved at right angles to the rail but cannot move longitudinally of the rail or transversely in the base plate. In this modified structure the wedge device consists 35 of a more or less triangular horizontal wedge plate 68 having one angular face engaging bearing surface 62, heretofore referred to, and on its opposite side an upwardly extending lug 70 extending parallel 40 with the rail entering, traveling along, and bearing against the wall of a recess 72 formed in the under side of the brace block 64. As in the previous construction this angular face between the left side of lug 70 and block 64 is inclined vertically downward into the wedge and member 68 whereby the opposing face of block 64 is caught under this wedge and cannot jump up. This brace block as in the preferred construction, is 50 provided with elongated slots 76 at a substantial angle to the slots 66, heretofore referred to, these slots in the case here illustrated being elongated parallel to the angular face 62 of the wedge.

55 The member 70, heretofore referred to, is provided with a plurality of transverse perforations 74 adapted to be selectively entered by cotter pin 75 corresponding in function to cotter pin 52 which is entered in the 60 last hole in the member 70 which is nearest adjacent to the edge 78 of bearing block 62 when the wedge 68 is driven to final adjustment.

As in the preferred construction, the intersecting points between the slots 66 and 76

are occupied by bolts 80 rising from the plate 10 tightenable by nuts 82. As in the preferred construction the device is adjusted by loosening these nuts 82, then driving the wedge 68 upward as viewed in Fig. 3, replacing the cotter pin 75 in the hole just then outside of the edge of the brace block and then tightening up the bolts 80 or equivalent fastening device.

In the particular case here illustrated, the 75 bolts 44 and 80 are shown as having countersunk heads entering the bottom of the plate 10 with nuts above the respective blocks 32 and 64, but these are wholly unessential details, forming no part of the invention, as 80 bolts or their equivalent may be inserted in any suitable manner.

In both constructions the brace block always moves only perpendicular to the rail, thus insuring the best possible action of the 85 device. The device is self contained on plate 10 which can be carried anywhere and secured to the rail through the agency of spikes passing through holes 84 provided for them.

Having thus described my invention what I claim as new and desire to secure by Letters Patent is:—

1. In mechanism of the class described, a plate for use over a tie, a rail across the plate, 95 a bearing block on the plate at one side of and beyond the rail, a wedge member slideable, and resting upon the plate, a brace block engaging the rail on one side and the wedge member on the other side, adapted as 100 the wedge is moved parallel with the rail to be moved thereby transversely of the rail, there being a portion on said bearing block extending over said wedge, securing members on the base plate passing through the 105 wedge and the bearing block, through elongated slots in the brace block and the wedge member at substantial angles to each other, so that the brace block can only move at right angles to the rail and the wedge can 110 only move transversely thereof to so move the brace block.

2. In mechanism of the class described, a plate for use over a tie, a rail across the plate, 115 a bearing block on the plate at one side of and beyond the rail, a wedge member slideable and resting upon the plate, a brace block slideable longitudinally of a vertical surface on the wedge inclined downwardly in the body of the wedge and outwardly from the 120 body of the block, a brace block engaging the rail on one side and the wedge member on the other side adapted as the wedge is moved parallel with the rail to be moved thereby transversely of the rail, there being 125 a portion on said bearing block extending over said wedge, securing members on the base plate passing through the wedge and the bearing block, through elongated slots in the brace block and the wedge member at 130

- substantial angles to each other, so that the brace block can only move at right angles to the rail and the wedge can only move transversely thereof to so move the brace block.
- 5 3. In mechanism of the class described, a brace block adapted to engage the rail having elongated slots in it at right angles to the rail, a wedge engaging the brace block and adapted to move transversely thereof to
- 10 move said brace block in the direction of the length of its elongated slots, there being also elongated slots in the wedge member overlapping the elongated slots of the brace block at such an angle thereto that the wedge
- 15 member can so move the brace block, a base plate sustaining the wedge and having supports rising therefrom through said elongated slots, and means on said supports for detachably securing the brace block and
- 20 wedge together.
4. In mechanism of the class described, a brace block adapted to engage the rail having elongated slots in it at right angles to the rail, a wedge engaging the brace block and adapted to move transversely thereof to move said brace block in the direction of the length of its elongated slots, said movement taking place longitudinally of a vertical surface on the wedge inclined downwardly
- 25 in the body of the wedge and outwardly from the body of the block, there being also elongated slots in the wedge member overlapping the elongated slots of the brace block at such an angle thereto that the wedge
- 30 member can so move the brace block, a base plate sustaining the wedge and having supports rising therefrom through said elongated slots, and means on said supports for detachably securing the brace block and
- 35 wedge together.
5. In mechanism of the class described, a base plate, a wedge member bearing upon

the base plate and movable transversely thereof so that one face of the wedge member engages a bearing surface on the base plate, a brace block for a rail fitting over the wedge member and engaged by it to be moved longitudinally of the base plate, and means engaging the base plate, wedge and brace block for detachably securing them together in different predetermined selective positions.

6. In mechanism of the class described, a base plate having a bearing face for a wedge extending across the base plate and a face at 55 a point remote therefrom and parallel thereto for a rail, a rail extending across the base plate bearing against said last mentioned face, a wedge having a relatively high portion bearing on said first mentioned face of 60 the base plate, and a lower base flange extending therefrom toward the rail, a brace block occupying substantially all of the space between the wedge flange and adjacent rail flange engaging the rail and resting 65 upon the base flange of the wedge and bearing against a wedge face formed on said base of the wedge angular to said first mentioned face of the wedge which engages the base plate, a bolt extending from the base plate 70 through intersecting elongated slots, one in the brace block, the other in the flange of the wedge and at right angles thereto, whereby on loosening the bolt the wedge may be moved to move the brace block and on 75 tightening the bolt the brace block and wedge are secured to the base plate.

In witness whereof, I have hereunto subscribed my name in the presence of two witnesses.
